EVAPORATOR FOR REFRIGERATING PLANTS

Raoul Bernat and Henri Bernat, Bordeaux,
FranceApplication June 7, 1933, Serial No. 674,755
In France June 10, 1932

2 Claims. (Cl. 62—126)

This invention relates to evaporators used in refrigerating machines.

It is an object of the invention to provide a vertical arrangement for two sets of tubes. One of the sets of tubes is exposed while the other set is positioned in a vertically disposed tank which is filled with a low freezing liquid which acts as a reservoir when the refrigerator is in operation and absorbs heat when the refrigerator is stopped.

A further object of the invention is to provide means for forcing any oil into an upper receiver which may accumulate in a lower receiver.

It is also an object of the present invention to provide means for creating a vacuum whereby the oil accumulated in the upper tank is extracted and returned in suitable amounts to the suction circuit.

A still further object of the invention is the formation of the sets of tubes into a grate formation, utilizing only two weldings.

With the above and other objects which will become apparent as the description proceeds, the invention comprises the arrangement and combination of parts as set forth in detail below, claimed in the claims and shown in the drawing, in which

Figure 1 is a diagrammatic view of the invention,

Figure 2 shows a front elevational view of a set of three tubes,

Figure 3 shows an exploded perspective view of portions of two tubes prior to assembly,

Figure 4 is a sectional view on the section line IV—IV of Figure 2, and

Figure 5 shows a detail view of the flap valve housing.

Referring to the drawing, the evaporator comprises the two receivers 1 and 2 between which extend the sets of tubes 3, 4 and 5 upon one side and the sets of tubes 6, 7 and 8 upon the other side, which latter tubes are contained in a tank 9.

Referring to Figure 2, each set of tubes comprises a main tube 8 upon which is welded a tube 21 which is bent in the form shown. Before welding, suitably shaped openings are provided in the tubes 8 and 21 (see Figure 3). These openings are brought into register and then the welding is carried out while held in the position shown in Figure 4. It will be noted that the tube 8 is slightly offset rearwardly in relation to the plane of the tube 21.

The liquefied gas is led from the condenser by means of the pipe 10, the end of which extends into the pipe 11 which latter pipe is of a substan-

tially larger diameter whereby a substantially annular space is provided between the telescoped ends of pipes 10 and 11.

The liquid when expanding causes the formation of a certain amount of vapor so that both liquid and gas will be conveyed into the receiver 1 by means of the pipe 12. Under these conditions the oil which may be carried by the liquefied gas entering the evaporator is expelled into the receiver 1. In addition, if oil should accumulate in the receiver or tank 2 while the refrigerator is not in operation, then such oil would penetrate into the annular space between pipes 10 and 11 and this oil would also be carried by pipe 12 into receiver 1.

Inside the upper part of the receiver or tank 1 there is provided a suction pipe 13 and a flap valve assembly. A valve 15 is located in the conduit connecting the suction pipe 13 and the housing 14 for the flap valve. A pipe 16 connects the evaporator with the suction end of the compressor through the assembly 14.

As shown in Figure 1 particularly, the upper ends of the sets of tubes 3, 4, 5, 6, 7 and 8 open into the receiver 1 at a higher level than the lower opening of the pipe 13. The oil carried up through pipe 12 consequently accumulates at the base of the receiver or tank 1.

The flap valve 19 is provided with vanes 17 and is of sufficient weight to create a difference in pressure of about 50 grs. per sq. cm. between the receiver 1 and the conduit 16. A sufficient value must be given to this difference in pressure so as to cause a suction of the oil accumulated at the base of the receiver 1 and then return it to the suction circuit.

The purpose of the valve 15 is to permit a free passage only to oil in the suction conduit. This valve cannot be dispensed with since it prevents large amounts of the liquid from flooding the compressor and thereby causing dangerous shocks. The flap valve 19 is provided with a lower spring 18 upon which the valve rests by means of the vanes 17 and an upper spring 20. The springs enable a noiseless operation of the valve.

The arrangement illustrated between pipes 10 and 11 for leading the oil from the lower receiver 2 to the upper receiver 1 facilitates greatly the entrainment of the oil during operation and also permits avoiding operating without oil when the apparatus is not functioning. As a matter of fact, during the stopping of the machine the lubricant fills the annular space in the telescope portions of the pipes 10 and 11 and as soon as the

machine is placed in operation the lubricant is entrained.

The suction pipe 13 opens at the lower part of the tank 1 as is clearly shown in Figure 1. Due to this construction the valve 15 which is at a higher level is sheltered from every obstruction which may be caused by impurities in the oil. The impurities will remain at the bottom of the receiver 1 and will not be entrained in the oil circulation. Due to this construction also the various other mechanisms of the apparatus will be preserved from the deleterious influence of the impurities.

The valve assembly 14 permits a constant pressure being maintained in the pipe 16 and consequently there is assured the entrainment of a constant quantity of gas and liquid. Due to this arrangement it is possible to avoid a sharp influx of liquid which would cause variations in the installation.

From the construction above described it is obvious also that if we assume a pressure p in the suction pipe 13 for the liquid, then the pressure P in the chamber 14 of the flap valve construction and in the conduit 16 is higher than the pressure in the suction pipe 13. In fact, a restricting element is formed by the cock valve 15 being interposed between the gas exhaust conduit and the chamber 14. This element 15 produces a fall in pressure tanks to which there

is obtained an automatic regulation of the quantity of liquid suctioned.

Having now particularly described and ascertained the nature of our invention and in what manner the same is to be performed, we declare that what we claim is:

1. An evaporator comprising an upper receiver, a lower receiver, pipes connecting said receivers and having their openings in the upper receiver located at a level above the bottom of said receiver, a first conduit connected to said lower receiver for leading liquefied gas thereto and terminating within said receiver and a second conduit connecting said lower receiver to said upper receiver and encircling the end of said first conduit for a portion of its length and spaced therefrom to provide a space between said conduits for the passage of liquid.

2. An evaporator comprising an upper receiver, a lower receiver, pipes connecting said receivers and having their openings in the upper receiver located at a level above the bottom of said receiver, a gas discharge conduit located in said upper receiver and having an opening located at the lower portion of said receiver, a flap valve communicating with said upper receiver in said gas discharge conduit and a restricting element upon said gas discharge conduit located between the opening thereof and said flap valve.
